FOOT-ARCH SUPPORT STRUCTURE

Walter Wisbrun, Cleveland Heights, Ohio

Application April 4, 1950, Serial No. 153,789

4 Claims. (Cl. 36—8.5)

1

Extended study of the internal mechanics of the foot shows that an arch support of the common form does not fully cover the physiological requirements. These requirements are: (1) To provide a corrective effect upon the deformed skeletal structure and to restore muscular equilibrium. (2) To eliminate the dead space between the foot and the sole and the upper of the shoe, a most important factor in the etiology of flat-foot. (3) To provide perfect coordination between the foot and the shoe. In accordance with the present invention, support structures may be had which now meet these important requirements. Other objects and advantages of the invention will appear from the following description.

To the accomplishment of the foregoing and related ends, said invention then comprises the features hereinafter fully described and particularly pointed out in the claims, the following description and the annexed drawing setting forth in detail certain illustrative embodiments of the invention, these being indicative, however, of but a few of the various ways in which the principle of the invention may be employed.

In said annexed drawing:

Fig. 1 is a side elevational view of the skeletal structure of the foot as by X-ray;

Fig. 2 is a plan view, as by X-ray, corresponding to Fig. 1, but with the terminal phalanges omitted;

Fig. 3 is an elevational view of the inner side of a shoe embodying the invention;

Fig. 4 is a vertical section thereof taken on a plane substantially indicated by line IV, Fig. 3;

Fig. 5 is a similar view of a modification; and

Fig. 6 is a plan view of a rear section blank which may be used for the assembly of the shoe-upper.

A brief consideration of the anatomy and physiology of the structure of the foot will assist in an understanding of the principles involved in the present invention.

In the normal function of the foot skeleton in walking an automatic alternation of the tarsal joints is involved between supination in the swinging phase, and pronation in the propelling phase. This rhythmical motion is carried out between the sub-talar foot plate on the one hand, and the leg and the talus on the other. The sub-talar foot plate is suspended on the talus on two coordinated rotary joints, the talo-navicular ball and socket joint, and the pivot joint between the sustentaculum tali and the corresponding groove of the infero-medial aspect of the collum tali.

Both these rotary joints are located on the medial side of the foot skeleton. In the swinging phase, the sub-talar foot plate is rotated downward upon these two rotary joints due to its own weight. This downward rotation of the sub-talar foot plate is combined with an external rotation of the leg. In the stance phase the leg is internally rotated, and the malleoli guide the talus into adduction, which creates pronation of the foot; in other words, brings the great toe in contact with the ground, which concludes the stance phase by repelling the foot from the ground. This rotary motion of the foot is transmitted through the leg and the entire body, creating centrifugal power, which substitutes and economizes the expenditure of muscle power.

The cuboid occupies a keystone position in the skeletal structure of the foot. It is the lateral portion of the so-called tarsal arch, a rigid structure composed of five tarsal bones, which rotates about the talo-navicular joint; and furthermore, strong connecting ligaments pull the anterior end of the calcaneus behind the cuboid rotating inferiorly in supination and superiorly in pronation. In standing, the cuboid is elevated in the normal foot, and in walking it rotates downward in the swinging phase and upward in the stance phase. This mechanism gradually deteriorates in flat-foot, the cuboid in conjunction with the anterior end of the calcaneus sags, and finally a lifting of the cuboid and the anterior end of the calcaneus in the stance phase fails to occur, and the typical weary and un-elastic flat-foot gait develops. Shoe manufacturers have attempted to utilize the keystone position of the cuboid by specifically building a cuboid support into the shoe. This however, proves wholly ineffective, because concentrated pressure in such a small area cannot be tolerated. Further attempts in the direction of extending the under-neath support further in a longitudinal direction on the shoe sole still did not eliminate the shortcomings inherent in foot supports as far as they actually provide supporting counter-pressure. It did not fulfill the expectation of eliminating the dead space between the foot at the instep and the shoe. I have found that the reason for this shortcoming was that such a support was of an area to equal the entire plantar fascia and the anterior and posterior foot cushions. A detailed study of the plantar portion of the foot shows that the plantar fascia really covers three longitudinal sections of the arch, there being septa or fascious tissue extending from the plantar fascia to the skeletal portions above, thus divid-

ing off three general compartments, an inner, a central, and a lateral, and in these compartments there are respective muscle groups extending generally fore and aft connected to the respectively adjacent portions of the skeletal system. The central muscle group is comparatively weak but the central portion of the plantar fascia is 3 to 4 mm. thick and runs sagittally from the under surface of the calcaneus to the plantar parts of the metatarso-phalangeal joints, while the medial and the lateral portions of the plantar fascia run transversely, joining on the dorsum of the foot. The central portion of the foot skeleton comprises the main weight-bearing part of the foot, the line of gravity and the axis of rotation of the talo-navicular joint crossing each other at the interval between the second and third metatarsal heads. The medial muscle group is the strongest, and the first metatarsal bone in conjunction with the medial cuneiform and the navicular has the greatest mobility of the three portions. The previously-mentioned up and downward motion of the cuboid about the talo-navicular ball and socket joint is joined by the first metatarsal bone. And conversely, the cuboid moves downward when the first metatarsal bone is rotated upward, and vice versa. The lateral portion or section of the foot structure takes the least part in supporting the body. The fourth and fifth metatarsals are movably connected with the cuboid, and their function is mainly to adapt the weight-bearing surface of the foot to uneven ground. For this purpose they are provided with a very strong muscle mantle. This tri-partite structure and function of the foot has heretofore not been taken account of in arch supports, but it should be. An important concept in the present invention is that an arch support which merely provides contact or counter-pressure on the under-surface of the foot skeleton is ineffective, and harmful by causing either periosteal irritation or pressure-atrophy of the muscle lying between the appliance and the bones, or both; and the present invention designs to strengthen or to restore respectively, the bracing effect, in the first place of the central portion of the plantar fascia. A medial extension of bracing or sling support to cover the medial portion of the plantar fascia up the inner surface of the instep is provided to support the talo-navicular articulation upon which the rhythmical play of the calcaneo-cuboid junction is centered. This is achieved by in effect restoring the bracing or sling effect of the plantar aponeurosis in this region. On the other hand the inferior bracing element adapted to the central and lateral portions of the plantar aponeurosis is kept on the order of a half inch distance from any bone surface. The pressure thus distributed over the entire extent of the medial and lateral muscle compartments restores the turgor of these muscle groups, or turns them in effect into hydraulic cushions, the upward and inward counter-pressure restoring the muscle equilibrium and the normal posture of the foot skeleton. By distributing the pressure over such a large surface, no concentrated points of irritation can result.

Flat-foot bone positions are shown in full lines in Fig. 1, and the normal by dotted lines N.

From the relationships in the bony structure, it is seen that the weight exerted through the leg is applied at a line of center of gravity c—c, Fig. 3, this lying in the middle muscle compartment. And the line of rotary motion d, Fig. 3, at the

talo-navicular joint converges to this line in the interval between the second and third metatarsal heads. The supporting pressure upon one foot must equal half of the weight of the entire body, and at times the whole weight, and this amount of pressure if concentrated upon one spot would be intolerable. By the provision of an extensive pliant support element or sling along the inner side of the instep the pressure is evenly distributed in accordance with the requirements of the support in a vertical direction and the counter-action of the inward roll or turn due to abduction in flat-foot.

The medial section of the foot participates only secondarily in the sagging of the foot, since the talus is seated on top of the calcaneus. For this reason it does not particularly need support by upward counter-pressure, because the sag of the talo-navicular joint is compensated by the lifting of the calcaneo-cuboid junction. The talo-navicular junction moves to the medial side in flat-foot, because lengthening of the foot is prevented by the traction of the central portion of the plantar fascia. The result is that the forefoot is abducted and that the ligaments of the medial capsule (the tensile strength of which is considerable in a longitudinal direction but much smaller transversely) are expanded transversely and yield more and more to the abduction of the forefoot. The medial capsule or portion at the inner side of the foot therefore is reinforced in the present invention by a pliant brace or sling which tightly encompasses the medial or inner side of the foot. Since the medial capsular ligaments are inserted at the under surface of the skeletal structure, the proper effect can only be obtained when actually the medial and part of the inferior surfaces of the arch are closely and continuously embraced. This purpose can only be achieved when there is supplied a close, pliant but firm support or sling against the medial or inner surface of the foot in effect in continuity with the rigid support of the central and lateral or outer portions of the plantar aponeurosis. Such an effect cannot be obtained either by a rigid pressure element on the medial side of the foot, or by merely taking in the medial part of the shoe-upper and narrowing the shank of the shoe. In the first case, pressure-atrophy of the crucial medial muscle portion would develop, as above pointed out. And in the second case, the greatest and most significant part of the dead space between the foot and the sole of the shoe would still remain. I therefore provide an elevated platform 2, Fig. 3 of the drawing, on the sole of a shoe, built in, this platform being in the sub-arch portion with respect to the foot, and sloping fore and aft at f and a, to the ball and heel respectively. This platform is relatively firm, as distinguished from a cushion, and may be made of any suitable material, to give a build up particularly for the central outer and central portions of the tri-partite structure of the foot. Thus, the platform is recessed or cut in at its intermediate zone i, and the extent to which it is thus recessed or narrowed at such intermediate portion may correspondingly be less than about 70 per cent of its width at maximum point, or in general 60-75 per cent. Joined to the recessed edge of the elevated platform 2, and in effect forming a continuation directed upwardly, but pliant instead of with the firmness of the said platform, is a support element 4, Fig. 4, which for convenience of manufacture may in some cases be a shoe upper or vamp element forming

the portion which contacts the instep or inner surface of the ankle between heel and ball of the foot. This element 4 is in effect a pliant sling which is secured below to the edge of the elevated platform 2 and thence extends upwardly to the top of the shoe. It is to be noticed that unlike an ordinary shoe-upper outline, the member 4 is strongly narrowed inwardly to engage against the foot, the leather or cloth blanks of which the shoe upper is assembled, being cut to a shape that when seamed together, the seam, as at 5, Fig. 3, draws closely in and narrows the space at such zone. Thus, as indicated generally at Fig. 6, the blank or the rear section 6 may have its forward edge 7 shaped so that when seamed with the co-acting edge portions 8 of the adjacent blank edges, there is a pronounced drawing in or narrowing. As the wearer's foot is then inserted in such an article of footwear, the outer surface of the foot is against the outer portion 9 of the upper, the base of the foot at the arch is supported by the platform 2, and the inner surface from thence up to the top of the shoe is supported by the strongly indented portion 4 of the shoe-upper, and the latter provides a pliant although firm support or sling against tendency to inward roll, while the base of the foot at the instep is supported by the relatively rigid platform 2. A support thus complete is afforded for the entire section of the foot between the ball B and the heel H of the shoe.

In some cases, instead of having the shoe upper per se constitute the sling or support element for the inner side of the instep, the support element 4', Fig. 5, can be generally shaped along the lines as foregoing, and likewise pliant, as of leather or fabric, be secured to the recessed edge of the platform support 2 below, and be secured to the top edge of the shoe-upper u, which latter may be of the usual external contour. In such case, there is a dead space between the shoe upper and the sling or support 4', but the latter snugly bears against the foot, and the dead space outside is of no moment insofar as the foot is concerned. This form of construction shows externally as the customary contour of a shoe, while the form in Fig. 4 shows externally a more deeply recessed contour.

Where high shoes, or boots, are to be equipped with the built-in support construction, the sling element need not be carried higher than the equivalent of the top of the low style or Oxford shoe. The feature in any case is the providing of a pliant snugly engaging support up along the whole of the inner surface of the instep and in continuity from an elevated support-platform under the sub-arch.

Withal, a complete buttress is provided at the instep, in general L-shape curvate form with base as a platform relatively firm and with inner edge

5
recessed, and the upwardly directed limb longer and more pliant.

Other modes of applying the principle of the invention may be employed, change being made as regards the details described, provided the features stated in any of the following claims or the equivalent of such be employed.

I therefore particularly point out and distinctly claim as my invention:

- 10 1. In footwear having a firm sub-arch support element secured above the shoe sole, said support being recessed toward the mid-line of the shoe at its inner edge, an extension support element therewith in pliant sheet form connected to the inner edge of said firm sub-arch support and extending up to anchorage all along its upper edge on a line at low shoe top level.
- 20 2. In footwear, a low shoe including a sub-arch firm support secured to the shoe sole, said support being recessed toward the mid-line of the shoe at its inner edge, and a support extension therefrom in pliant sheet form having its lower edge anchored along the inner edge of said firm support and its top edge anchored all along the shoe top-edge.
- 25 3. Footwear, having a pliant sling support with continuous anchorage all along the top edge of a low shoe upper and extending down along the inner side of the shank, and an elevated platform secured to the sole under the arch, said platform being recessed toward the mid-line of the shoe at its inner edge, to which edge such pliant sling is fastened.
- 30 4. A built-in foot arch support in footwear, comprising a buttress elevation secured to the sole, said buttress elevation being recessed toward the mid-line of the shoe at its inner edge, and a support surface continuing up from the inner edge of said buttress at the inner side of the arch to an upper substantially horizontal line of anchorage at the level of a low shoe top edge.
